UNITED STATES PATENT OFFICE.

JOSEPH P. SANDER, OF SPOKANE, WASHINGTON, ASSIGNOR TO SPOKANE MAIL EQUIPMENT COMPANY, OF SPOKANE, WASHINGTON.

MAIL-CONTAINER.

1,151,827.

Specification of Letters Patent. Patented Aug. 31, 1915.

Application filed September 2, 1914. Serial No. 859,864.

To all whom it may concern:

Be it known that I, JOSEPH P. SANDER, a citizen of the United States, residing at Spokane, in the county of Spokane and State 5 of Washington, have invented certain new and useful Improvements in Mail-Containers, of which the following is a specification.

This invention relates to improvements in mail bags, and has to do more particularly 10 with an improved container, which is adapted to receive a number of mail bags or parcel post articles, the invention not being intended primarily to contain loose individual and small articles, such as letters.

15 One of the objects of the invention, in addition to the foregoing, is to provide a mail bag container equipped with transfer lines extending from the top and bottom thereof so that the bag or container can be transferred by mail catching mechanism from a 20 car to a station, or vice versa.

A further object is to provide a mail container, which is strong in construction and light in weight, and which is almost entirely 25 flexible so as to render the same capable of being handled by mail catching or transferring mechanism.

A further object of the invention is to 30 swivel the container in supporting relation on the upper transfer line and to also yieldingly mount the container thereon, for purposes which will hereinafter more fully appear.

Other objects and features of the invention 35 will be more fully described in connection with the accompanying drawings, and which will be more particularly pointed out in and by the appended claims.

In the drawings:—Fig. 1 is a view in 40 elevation of my improved mail container. Fig. 2 is a view thereof with the outer cover or casing omitted. Fig. 3 is a plan view of the structure shown in Fig. 2.

Like characters of reference designate 45 similar parts throughout the different figures of the drawings.

As illustrated, my invention includes a skeleton frame structure comprising upper and lower hoops 1 and 2, which will prefer- 50 ably be made of steel, and which need not be entirely rigid although they will be formed sufficiently rigid to normally maintain their form. Furthermore, I do not deem it absolutely essential that they should be circular

in form, although I prefer this type. The 55 hoops 1 and 2 are connected by flexible inextensible supporting lines which may be in the form of chains 3, the upper ends thereof being connected to the upper frame member or hoop 1 and the lower ends thereof being 60 connected to the lower frame member or hoop 2, in any desirable manner. The frame structure also includes flexible cover attaching members, which may be in the form of flexible fabric web strips 4. Said strips 65 are shown secured to the upper and lower frame members by having their ends looped over said members and being secured by means such as rivets 5.

To the upper frame member 1, I attach 70 transfer supporting lines 6, the free ends of which are secured to a hanger member, which may be in the form of a disk 7. A hanger bolt 8 is slidably and rotatively disposed in the hanger member 7 so as to form 75 a swivel juncture therewith. The bolt 8 is provided with a spring abutment which may comprise a washer 9 and a nut 10, and interposed between the abutment and said hanger disk 7, is an expansively acting spring 11, 80 which serves to neutralize jars and jolts to which a loaded container may be subjected thereby greatly relieving the strain thereon. Furthermore, the swivel supporting connection permits of the whirling motion which is 85 imparted to a transfer container in the operation of transferring the same from a running car to a station, or vice versa. The upper end of the bolt 8 is provided with an eye 12 and a supporting transfer line, in the 90 form of a chain 13, has its lower end connected with said eye. The upper end of said chain is provided with a ball device 14, for connection with the mail catching apparatus. At the lower end of said structure, 95 I provide a depending transfer line or chain 15, having a suitable head structure 16 for co-operation with the mail catching apparatus. The depending transfer line 15 is connected with a lower transfer member or 100 disk 17 by a swivel connection 18. The lower transfer member 17 is connected by chains 19 with the lower frame member 2.

The frame structure just described is enclosed by a preferably flexible casing or cov- 105 ering 20, which is provided with a flap 21, which may be opened and closed for access to and from the container. Suitable fasten-

ing devices 22 serve to maintain the flap closed, and at 23, I have shown mail bag contents. The cover 20 may be sewed or otherwise secured to the web strips 4, and the 5 upper and lower disks 7 and 17 serve to hold end portions of the cover from falling downwardly into the hoops, the chains 6 and 19 also supporting the tops and bottoms of the cover from collapsing inwardly.

10 I may provide a bottom which might be secured in any desirable manner in the lower hoop 2, but in the absence of such bottom, the chains 19 and disk 17 perform this function, it being understood that the cover 20 15 will be made of very heavy strong material.

It will now be seen that while the structure includes substantially rigid upper and lower frame members 1 and 2, still, the container is almost entirely flexible both as 20 regards indentation of its side or movement of the frame members toward each other, thereby causing the bag to act practically in the same manner as the bag which is entirely flexible in that it can yield in almost 25 every direction to shocks and strains. Furthermore, the supporting lines or chains 3 relieve the cover of the weight of the load, thereby rendering the container much stronger than if it were made wholly of fabric material.

30 It is believed that the advantages and utility of the invention will be fully understood from the foregoing description, and while I have herein shown and described 35 one specific form of my invention, I do not wish to be limited thereto except for such limitations as the claims may import.

I claim:

1. In a mail bag container, upper and 40 lower substantially rigid frame members, flexible inextensible lines connecting said frame members to support the lower from the upper, fabric web strips having their ends looped over and fixed to said frame 45 members, a hanger member, flexible inextensible supporting lines connecting said hanger member with said upper frame member, a supporting bolt slidable and rotatable in said hanger member to form a swivel connection and having a spring abutment, a supporting spring interposed between said abutment and said hanger member, an upper supporting transfer line connected with said bolt, a lower transfer member, flexible 50 inextensible lines connecting said lower transfer member with said lower frame member, a transfer line depending from said lower transfer member, and a flexible covering inclosing said parts and secured to said web 55

strips and provided with an openable flap, 60 substantially as described.

2. In a mail bag container, a frame structure comprising upper and lower frame members, flexible lines connecting said frame members to support the lower from the upper, fabric web strips secured to said frame members, an upper transfer line having a swivel spring connection with said frame structure, a lower transfer line depending from said frame structure, and a flexible 65 cover inclosing said frame structure and being secured to said web strips, substantially as described.

3. In a mail bag container, a flexible frame structure comprising upper and lower frame 75 members, flexible inextensible means connecting said frame members, fabric strips connected with said frame members, and a flexible covering inclosing said structure and being secured to said strips, substantially as 80 described.

4. In a mail bag container, a flexible inextensible skeleton frame structure including fabric portions, a cover of flexible material inclosing said structure and secured to said 85 fabric portions, and upper and lower transfer mechanism extending from the ends of said structure and supporting the cover against collapse inwardly, substantially as 90 described.

5. In a mail bag container, a flexible metallic skeleton frame structure including fabric portions, a cover inclosing said structure and formed of flexible material and being secured to said fabric portions, transfer 95 devices extending from said frame structure, and a yielding swivel device for connecting one of said transfer devices to said frame structure, substantially as described.

6. In a mail bag container, a skeleton 100 frame structure including substantially rigid upper and lower hoops, chains for supporting the lower hoop from the upper hoop, fabric strips extending from hoop to hoop, a flexible covering inclosing said frame structure and secured to said fabric strips, a lower transfer device forming a bottom for 105 said structure, an upper transfer device, and a swivel spring means for connecting said upper transfer device with said frame structure to yieldingly support the latter, substantially as described.

In testimony whereof I affix my signature in presence of two witnesses.

JOSEPH P. SANDER.
